UNITED STATES PATENT OFFICE.

EDWIN E. SLICK, OF WESTMONT BOROUGH, PENNSYLVANIA.

METALLIC RAILWAY-TIE.

Specification of Letters Patent.

Patented June 8, 1915.

1,142,278.

Application filed August 14, 1914. Serial No. 856,734.

To all whom it may concern:

Be it known that I, EDWIN E. SLICK, a citizen of the United States, residing in the borough of Westmont, in the county of Cambria and State of Pennsylvania, (whose post-office address is Johnstown, Pennsylvania,) have invented certain new and useful Improvements in Metallic Railway-Ties; and I do hereby declare the following to be a full, clear, and exact description of the invention, such as will enable others skilled in the art to which it appertains to make and use the same.

My invention relates to a metallic railway tie formed of a corrugated or grooved plate with upwardly projecting rail chairs mounted thereon and clips and bolts adapted to secure the rail to the chairs.

Certain of the objects of my invention are:—to provide a tie that will possess all of the necessary qualities for the purpose intended; to use in the construction thereof material such as will permit a light weight tie to be constructed simply and economically and at the same time provide a tie which may be easily put in place and the rails readily adjusted thereon.

Another object of my invention is to provide an insulation between the rail chairs and the cross members of the tie to adopt the tie for use in connection with railway signaling apparatus.

Referring now to the accompanying drawings in which similar letters of reference indicate corresponding parts: Figure 1 is a side elevation of my improved metallic railway tie with the rails in place, showing in this case the insulation between the rail chairs and cross member of the tie; Fig. 2 is a plan of Fig. 1 with the right hand rail and clips shown in dotted lines and with the right hand bolts removed; Fig. 3 is a cross section taken on line III—III of Fig. 1; Fig. 4 is an end elevation of my improved tie without the insulation between the rail chairs and the cross member of the tie.

The cross member 1 of my improved tie is stamped or rolled into a species of corrugated shape which has a depressed longitudinally extending member 2, lateral extending substantially flat upper flanges 3 with outwardly and downwardly projecting side members 4. The rail chairs 5 may be formed by rolling or stamping plates into the desired shape, and are each provided

with laterally extending bottom flanges 6 adapted to rest on and be secured to the flanges 3, and also have rail seat portions 7. The flanges 6 are perforated at 8, to register with the perforations 9 in the laterally extending flanges 3. Rivets or bolts 10 pass through the said perforations 8 and 9 and securely fasten the rail chair to the cross members of the tie.

When it is desired to insulate the rail chairs from the cross member of the tie, washers 11 are provided. The insulation strips 12 and 13 are inserted respectively between the flanges 6 and 3 and the flanges 3 and the washer 11. An insulation tube 14 surrounds the portions of the rivets or bolts 10 intermediate the flange 6 and the washer 11.

Clips 15 are formed with a downwardly projecting lug 16 and a rail receiving groove 17. The lugs 16 are adapted to be received in the slots 18 of the rail chairs 5 and are thereby prevented from shifting their position when they are placed in their desired positions with the surfaces of the grooves 17 bearing upon the edges of the bottom flanges of the rails 19. The rail chairs 5 and the clips 15 are respectively provided with perforations 20 and 21 which are adapted to receive bolts 22. Nuts 23 and lock washers 24 are provided for the bolts 22 and by means of said clips, bolts, nuts and lock washers, the rail 19 may be securely fastened to the rail chair. The rail chairs which extend longitudinally with the cross members, and transversely of the rails are open at either end to permit the bolts to be readily inserted and to allow wrenches to be applied without difficulty to the bolts 22 within the said open ends. Rail chairs that extend longitudinally of the rails and are open at each end, make it necessary to apply the wrenches to the bolts of the rail fastening clips directly below the rails which is very difficult and impracticable. In my improved tie I eliminate this disadvantage.

The lower cross member 1 is made of special longitudinally corrugated cross section as shown, which adds to its stiffness and strength, is further stiffened and strengthened at and near the rail seats by the rail chair 5 which may be made of length and strength sufficient to properly distribute the load to the cross member and thence to the ballast, while the corrugations in the cross

member also serve to prevent it from shifting on the ballast and hold it securely in position thereon.

Although I have shown and described my invention in considerable detail, I do not wish to be limited to the exact construction shown and described, but may use such substitutions, modifications or equivalents thereof, as are embraced within the scope of my invention, or as pointed out in the claims.

Having thus described my invention what I claim and desire to secure Letters Patent is:—

15 1. A metallic railway tie comprising a trough section, with integral wings projecting laterally therefrom and rail chairs of inverted channel section with laterally extending lower flanges, mounted on the said wings.

20 2. A metallic railway tie comprising a longitudinally corrugated plate, and rail chairs of inverted channel section with laterally extending lower flanges attached to the upper portion of the side corrugations thereof.

25 3. A metallic railway tie comprising a corrugated plate provided with a central depression and two integral inverted trough shaped side portions, rail chairs of inverted channel section with laterally extending lower flanges attached to the upper portions of the trough shaped side portions.

30 4. A metallic railway tie comprising a plate provided with a central longitudinally extending depressed portion, integral laterally extending upper flanges adjoining the said depressed portion, outwardly and downwardly projecting portions adjoining the lateral extending flanges, and rail chairs of inverted channel section with laterally extending lower flanges attached to the upper surfaces of the laterally extending flanges.

35 5. A metallic railway tie comprising a longitudinally corrugated plate, integral wings projecting laterally therefrom, rail chairs of inverted channel section with laterally extending lower flanges attached to the said wings, and means for fastening the rails to the rail chairs.

40 6. A metallic railway cross-tie comprising a lower plate member, inverted trough shaped rail chairs of inverted channel sec-

tion with laterally extending lower flanges mounted thereon, and extending longitudinally of the plate member, said chairs being open at each end.

45 7. A metallic railway cross tie comprising a lower plate member, inverted trough shaped rail chairs of inverted channel section with laterally extending lower flanges extending longitudinally thereof, said chairs being open at each end, insulation intermediate the rail chairs and the plate member of the tie.

50 8. A metallic railway tie comprising a longitudinally corrugated plate, rail chairs of inverted channel section with laterally extending lower flanges attached to the upper portions of the side corrugations thereof, said rail chairs extending longitudinally of the plate member of the tie and being open at each end.

55 9. A metallic railway tie comprising a trough plate section, integral wings projecting laterally therefrom, rail chairs of inverted channel section with laterally extending lower flanges attached to the upper portion of said wings, said rail chairs extending longitudinally of the trough plate and open at each end.

60 10. A metallic railway tie comprising a trough plate section, integral wings projecting laterally therefrom, rail chairs of inverted channel section with laterally extending lower flanges attached to the upper portion of the said wings, insulation intermediate the rail chairs and the plate section, and means for fastening the rails to the chairs.

65 11. A metallic railway tie comprising a trough plate section, integral wings projecting laterally therefrom, inverted channel rail chairs with laterally projecting lower flanges attached to the upper portion of said wings, clamps and bolts adapted to fasten the rails to the said chairs, slots in the upper surface of the rail chairs and lugs on the said clips adapted to be inserted in said slots.

70 In testimony whereof I hereto affix my signature in the presence of two witnesses.

EDWIN E. SLICK.
